UNITED STATES PATENT OFFICE.

ABUNDIUS GRAVEL, OF TOLEDO, OHIO, ASSIGNOR TO THE WILLYS-OVERLAND COMPANY, OF TOLEDO, OHIO, A CORPORATION OF OHIO.

REAR-DECK CONSTRUCTION.

1,416,816.

Specification of Letters Patent. Patented May 23, 1922.

Application filed February 13, 1918. Serial No. 216,853.

To all whom it may concern:

Be it known that I, ABUNDIUS GRAVEL, a citizen of the United States, residing at Toledo, in the county of Lucas and State of Ohio, have invented certain new and useful Improvements in Rear-Deck Constructions, of which I declare the following to be a full, clear, and exact description.

This invention relates to improvement in the rear deck construction of motor vehicles. In certain types of motor vehicles, more particularly coupes and runabouts or roadsters, it is customary to provide a rear deck having a compartment therein for the storage of miscellaneous articles carried by the driver, which compartment is closed by a lid hinged to the rear deck and closing the opening to said compartment.

The principal object of my invention is to provide a rear deck construction of such a nature that a joint will be made between the lid closing the opening to said rear deck compartment and the deck so as to prevent water from running down into the compartment.

Further objects, and objects relating to economies of manufacture and details of construction, will definitely appear from the detailed description to follow.

I accomplish the object of my invention by the devices and means described in the following specification.

A structure constituting a preferred embodiment of my invention is illustrated in the accompanying drawing, forming a part of this specification, in which:

Fig. I is a fragmentary perspective view of the rear deck of a coupe embodying my invention.

Fig. II is a view similar to Fig. I but showing the rear lid raised and supported in raised position.

Fig. III is a detail, sectional view taken on the line III-III of Fig. I, and

Fig. IV is a detail, sectional view taken substantially on the line IV-IV of Fig. I.

In the drawing, similar reference numerals refer to similar parts throughout the several views, and the sectional views are taken looking in the direction of the little arrows at the ends of the section lines.

Considering the numbered parts of the drawing, I have shown a motor vehicle 10 having a rear deck 11 which is provided with a storage compartment 12, which is

closed by the lid 13, the rear portion of said lid being curved downwardly to conform to the shape of the rear deck, as clearly shown in Fig. I of the drawing. The lid 13 is hinged to the rear deck 60 by means of the hinges 14 which are secured to the front edge of the lid at 15 and pivotally mounted on the brackets 16, which are carried by the plates 17 secured to the deck and disposed within the compartment formed therein so that the hinges are effectually concealed. The toggle links 18 are provided, connected to the edge of the rear deck and to the lid so as to aid in supporting the lid in raised position. The 70 frame 19 runs around the edge of the opening in the rear deck and is provided with an inwardly extending flange 20 adjacent its lower edge. The strip 21 is secured to the inner edge of this flange, as shown in 75 Figs. III and IV, said strip being slightly wider than the flange 20 and the lower edge of said strip being flush with the lower edge of the frame 19 so that a gutter is formed by the flange 20 and the strip 21 which runs 80 around the edge of the opening in the rear deck. Another strip 22 is secured to the upper edge of the frame 19 and extends slightly above the upper surface of the rear deck, as shown in Fig. IV, and a similarly 85 located rubber strip 25 is secured to the upper edge of the frame 19 across the front edge of the opening. Strips 25 and 22 are so located that, when the lid 13 is in place, the metal portion 23 forming a part of the 90 lid rests upon the strips 22 and 25. The front edge of the frame member of the lid 13 is concave as at 24, so as to allow the front edge of the lid to swing freely around the upper edge of the strip 25 and also so 95 that any water which may run into said joint may drain down into the gutter formed by the flange 20 and the strip 21.

From the description of the parts given above, the operation of this device should 100 be very readily understood. The manner of hinging the lid with reference to the rear deck is not particularly new and forms no part of my invention, which has to do solely with the means for preventing water 105 from running into the compartment. It will be apparent that any water which may run down the rear deck into the joint at the front of the lid will drain down into the gutter formed by the flange 20 and the 110

strip 21 and will run down said gutter to the rearward edge of the opening where it will be directed rearwardly and will drain out without running into the compartment at all. The strips 22 and 25 form a firm support for the lid and tend to make a watertight joint therefor.

I am aware that the particular embodiment of my invention, which I have particularly described and shown in the accompanying specification, is susceptible of considerable variation without departing from the spirit of my invention, and, therefore, I desire to claim my invention broadly, as well as specifically, as indicated by the appended claims:

Having thus described my invention, what I claim as new and desire to secure by Letters Patent, is:

1. The combination with a vehicle provided with a rear deck having a storage compartment formed therein and a suitably hinged lid closing said compartment, of a frame secured to the inner side of said rear deck adjacent to the edges of the opening of said compartment, and conforming throughout its entire length to the contour of the lid said frame being provided with an inwardly extending flange; a metallic strip secured to the inner edge of said flange, and projecting slightly above the upper portion of said flange, forming a gutter around the edge of said compartment opening; and a strip secured to said frame, the upper part thereof projecting slightly above the upper surface of said deck.

2. The combination with a vehicle pro-

vided with a rear deck having a compartment therein and a lid suitably hinged and closing said compartment, of a frame extending around the opening of said compartment and provided with a gutter opening upwardly at the forward end and sides of said frame and opening rearwardly and outwardly of the compartment at the rear end of said frame; and a strip secured to the upper part of said frame and adapted to be engaged by the lid when in closed position.

3. The combination with a vehicle provided with a rear deck having a compartment therein and a suitably hinged lid closing said compartment, of a frame surrounding the opening for said compartment in said rear deck and provided with a gutter at the lower edge thereof extending entirely around the opening and opening upwardly on the forward end and sides of said opening and opening rearwardly at the rear end of said opening; and a lid supporting frame secured to said deck frame and extending slightly above the surface of said deck.

4. The combination with a vehicle provided with a rear deck having a storage compartment therein and a lid hinged to swing bodily outwardly for closing said compartment; of a frame surrounding the opening of said compartment and provided with a gutter extending entirely therearound and opening upwardly at the forward end and sides of said frame and rearwardly at the rear end of said frame.

In testimony whereof, I affix my signature.

ABUNDIUS GRAVEL.
